UNITED STATES PATENT OFFICE.

JOHN T. McLEAN, OF BROOKLYN, NEW YORK.

DESIGN FOR A BOX.

Application filed May 29, 1924. Serial No. 9,748. Term of patent 7 years.

To all whom it may concern:

Be it known that I, JOHN T. McLEAN, a citizen of the United States of America, residing at Brooklyn, in the county of Kings and State of New York, have invented a new, original, and ornamental Design for a Box, of which the following is a specification, reference being had to the accompanying drawing, forming part thereof.

I claim:—

The ornamental design for a box, as shown.

JOHN T. McLEAN.
